CONTROL DEVICE FOR SWITCHES OR
THE LIKEEarnest J. Dillman and Jack E. Fleury, Detroit,
Mich., assignors to Detroit Lubricator Com-
pany, Detroit, Mich., a corporation of Michigan

Application February 28, 1944, Serial No. 524,228

1 Claim. (Cl. 74—532)

1

This invention relates to new and useful improvements in devices for actuating and for determining the actuation of a reciprocated control device, such as a switch or the like.

An object of the invention is to provide an actuating device which will automatically function to lock or hold the control device in actuated position upon operation thereof.

Another object is to provide an actuating device which dominates the operation of a control device by its normally actuating operating means.

The invention consists in the improved construction and combination of parts to be more fully described hereinafter and the novelty of which will be particularly pointed out and distinctly claimed.

In the accompanying drawing to be taken as a part of this specification, there is fully and clearly illustrated a preferred embodiment of the invention, in which drawings:

Figure 1 is a view of the control device partially diagrammatic and in section and operatively related to the actuating device which is shown in vertical section on the line 1—1 of Fig. 2.

Fig. 2 is a view in section on the line 2—2 of Fig. 1;

Fig. 3 is a detail view also in section on the line 1—1 of Fig. 2 but showing the actuating device in locked position, and

Fig. 4 is a detail view on the line 4—4 of Fig. 3 and also showing the actuating device in locked position.

Referring to the drawings by characters of reference, 1 designates generally a supporting structure or casing which contains and supports the reciprocated control device 2 such as a snap-acting electric switch having a fixed contact 3 and a movable contact carried by an overcenter switch arm 4 which is pivotally supported, as at 5. Operable with the arm 4 there is a toggle spring 6 for quick and snap action movement of the arm 4 which is reciprocated by a rod 7 which may be of electric insulating material and has in its rear face or side opposed knife edges 8 providing a vertical slot through which extends a normally rigid resilient switch operating blade 9, carried by a bell crank type operating lever 10. The blade 9 is adjustably held under tension by an adjustment screw 11 so that the resistance of the blade 9 to movement relative to the lever 10 may be determined. The lever 10 is pivotally supported, as at 12, and has its arm 13 movable between spaced stop members 14, 15. The lever 10 is urged toward switch open position by a spring 16 held under compression by the structure 1 and acting

2

against the lever arm 13, normally tending to hold the arm 13 against the stop member 14. The switch 2 is moved to closed position by a power element 17 operable by temperature or pressure and comprising an expansible, collapsible member 18, such as a metal bellows, having a thrust member 19 engaging and acting on the lever arm 13 against the force of the spring 16.

Mounted on the casing 1, there is a housing member 20 containing a bell crank type lever 21 journaled on a shaft 22 extending between the side walls 23, 24 of the housing member. The lever 21 has an operating arm 25 which extends into the casing 1 through a wall slot 26 and into spaced opposing relation to the free end portion of the blade 9. The lever 21 has a horizontal arm 27 to which is anchored one end of a helical coil spring 28 having its one end adjustably supported by an adjustment screw 29 carried by and extending downward through an aperture in the top wall 30 of the housing member 20. The spring 28 urges the lever arm 27 into engagement with a longitudinally reciprocal shaft 31 supported by and extending between the casing side walls 23, 24 and extending through apertures 32, 33 respectively in said walls. The shaft 31 limits the movement of the lever 21 by the spring 28 and determines the force of the spring which opposes movement of the lever arm toward the switch operating blade 9. The top casing wall 30 carries an automatic operating means 34 having a cup-like casting 35 which is closed by a movable wall member 36 such as a metal bellows facing the lever arm 27 and providing a pressure chamber 37 having an inlet connection 38 for connecting the chamber 37 to a source of fluid pressure which, for example, might be the high side or condenser pressure of a refrigerating apparatus. Secured to the head or end wall of the bellows 36 there is a thrust member or push rod 39 having a conical free end portion seating in a conical recess 40 of a socket member 41 rigidly mounted on the lever arm 27.

Carried by the shaft 31 and rigidly secured thereto, there is a cylindrical abutment member 42 mounted on one end of the shaft 31 and positioned in the aperture 33 for supporting its shaft end. The member 42 is provided with an abutment flange 43 engageable with the outside face of the wall 24 to limit inward movement of the abutment member 42 into the housing 20. The other end portion of the shaft 31 extends through a cup-like retainer and guide member 44 secured to the outside face of the wall 23 and having an aperture through its bottom wall aligned with the

aperture 32. Secured on the end of the shaft 31 within and projecting from the member 44 there is a cylindrical button 45 reciprocally guided in the member 44 and which seats inward against a helical coil spring 46 positioned within the member 44. The spring 46 tends to urge the shaft 31 forwardly to bring the abutment member 42 into overlying relation to the lever arm 27 and urges the end face 47 of the abutment member 42 into endwise engagement with the side face or edge of the arm 27.

The height of the base of the socket 49 in the thrust receiving or socket member 41 above the lever fulcrum or shaft 22 is such relative to the resistances of the spring 28 and bellows 36 and to the lengths of the lever arms through which the spring 28 and rod 39 act on the lever 21 when the mechanism is in inactive position, Fig. 1, that the increasing lever arm of rod 39 upon its downward movement serves to overcompensate for the resulting increase in the resistance to and caused by its downward movement. The compensation, is also sufficient to take up or overcome the resistance of the leaf spring 9 and the overcenter spring 6 so that the pressure in chamber 37 which will initiate movement of the lever 21 against the resisting forces will cause a complete movement of the lever through its range of travel which will open the switch 2 and position the arm 27 below the plane of the abutment member 42. Accordingly, the abutment face 47 and the arm 27 may have rounded marginal edges as would result from their formation by a bending operation and it is not necessary to have the fine adjustment of parts which would provide simultaneous locking movement of abutment member 42 and overcenter or switch opening movement of arm 4. The overcompensated travel of lever 21 requires only that the abutment member 42 move into locking position after the lever 21 has opened the switch 2.

The operation of the actuating device is as follows: Assume for example that the power element 17 is connected say to the suction or return line of a refrigerating apparatus and the spring 16 is adjusted or set to determine the low side pressure at which operation of the refrigerating apparatus is to be started by closure of the switch 2 and that the power element or automatic operating means 34 is connected as above noted to the system high side. The spring 28 is adjusted by the screw 29 to determine the pressure in the system high side at which the lever arm 25 will be moved to the position shown in Fig. 3 wherein the switch 2 will be moved to open position to stop operation of the system. If for any reason the high side pressure, and therefore the pressure in the actuating device chamber 37 increases above the desired limit so that the lever 21 is moved to engage the blade 9 and flex it toward the right relative to lever 10 when facing Fig. 1,

then when the rod 7 has been moved sufficiently to move the switch arm 4 overcenter, the lever arm 27 will be moved below the abutment member 42 so that the spring 46 will pull the abutment member 42 inward into overlying relation to the lever arm 27, as shown in Figs. 3 and 4. The flange 43 will engage the wall 24, thereby limiting the movement of the abutment member 42 by the spring 46. Accordingly, the lever 21 will be held and locked in its operated position, thereby holding the switch 9 in open position against any force of the power element 17 tending to move the switch 2 to closed position. Operation of the lever arm 13 by the power element 17 will serve merely to flex the blade 9 without any resulting movement of the rod 7. The refrigerating apparatus may be placed in operation by pushing inward on the button 45 to move the abutment member 42 out of overlying relation to the lever arm 27 so that, assuming that the pressure has dropped to a pressure in the system high side, and therefore in the chamber 37 lower than the pressure at which element 34 initiated movement of the lever 21, the spring 28 will pull the arm 27 up to its limit against the shaft 31.

What is claimed and is desired to be secured by Letters Patent of the United States is:

In a control device, a casing having spaced walls, a lever between and movable in a plane parallel to said walls, one of said walls having a cylindrical guide opening therethrough, a cylindrical abutment member reciprocally fitting in and projecting from both ends of said opening, said abutment member having its inner end engaging the side of said lever, means urging said abutment member against said lever, a stop flange at the outer end of said abutment member and engageable with said one of said walls to limit inward movement of said abutment member by said urging means, the other of said walls having an aperture therethrough aligned with said guide opening, a rod projecting from said abutment member and extending through said aperture, a spring urging said lever against said rod, and means to move said lever away from said rod and out of the path of movement of said abutment member so that said urging means can move said abutment member into the path of movement of said lever by said spring.
